Primary Examiner — Elizabeth Albert(74) *Attorney, Agent, or Firm* — Global IP Services;
Tianhua Gu(57) **CLAIM**

The ornamental design for a folding pen, as shown and described.

DESCRIPTION

FIG. 1 is a front elevation view thereof;
FIG. 2 is a rear elevation view thereof;
FIG. 3 is a left side elevation view thereof;
FIG. 4 is a right side elevation view thereof;
FIG. 5 is a top plan view thereof;
FIG. 6 is a bottom plan view thereof;
FIG. 7 is a front elevation view showing a folded status thereof;
FIG. 8 is a front-top perspective view thereof;
FIG. 9 is a rear-top perspective view thereof;
FIG. 10 is a front-bottom perspective view thereof; and,
FIG. 11 is a rear-bottom perspective view thereof.

1 Claim, 6 Drawing Sheets(56)
